UNITED STATES PATENT OFFICE.

HARRY ARTHUR FOOTHORAP, OF HARRISBURG, PENNSYLVANIA, ASSIGNOR TO
ELLIOTT-FISHER COMPANY, A CORPORATION OF DELAWARE.

WRITING ADDING MACHINE.

Application filed July 19, 1921. Serial No. 485,804.

To all whom it may concern:

Be it known that HARRY A. FOOTHORAP, a citizen of the United States, residing at Harrisburg, in the county of Dauphin and State of Pennsylvania, has invented certain new and useful Improvements in Writing Adding Machines, of which the following is a specification, reference being had therein to the accompanying drawing.

This invention relates to writing adding machines, and more particularly that type which includes in its organization a relatively movable frame and carriage, and both printing and adding mechanism which are simultaneously operated upon the depression of keys to record and register values.

The object of the invention is to combine with one or more column registers a plurality of registers of the type known as crossfooters, arranged to be operated either one at a time or simultaneously in correspondence with the operation of the column register or column registers.

Another object of the invention is to provide a plurality of automatically controlled registers capable of addition or subtraction and operated by common operating means, as for instance, keys so that said registers may be operated in various operative combinations, either one at a time for addition or subtraction, simultaneously for addition or subtraction, or either singly or simultaneously one for addition and the other for subtraction.

Another object of the invention is to combine with a series of column registers, a plurality of additional registers or crossfooters operated simultaneously with the column registers, or certain of them, and automatically controlled individually for addition or subtraction.

Another object of the invention is to provide, in a machine of this character, a common restoring mechanism for a plurality of registers and automatic mechanism for locking the keys after each operation of either register and for retaining the keys in locked condition as long as there is any possibility of misoperating a register through the depression of a key.

To the accomplishment of these objects and others subordinate thereto, one embodiment of the invention resides in the construction and arrangement of parts herein-after more fully described, illustrated in the

accompanying drawings and defined in the appended claims.

In said drawings

Figure 1 is a plan view of a portion of an Elliott-Fisher bookkeeping machine equipped in accordance with my invention.

Figure 2 is a front elevation of the frame with the carriage removed.

Figure 3 is a side elevation of the crossfooter casing.

Figure 4 is an elevation of the other side of the crossfooter casing.

Figures 5 and 6 are detailed views of the two master wheel locks and release keys.

Figure 7 is a more or less diagrammatic front elevation on a somewhat enlarged scale.

Figures 8 to 11 inclusive, are a series of front elevations showing, in progressive positions, certain elements of the master wheel and key locking mechanism.

Figures 12 and 13 are detailed sectional views on the lines 12—12 and 13—13 respectively, of Figure 7.

Figure 14 is a detailed view of certain elements of the master wheel and key locking mechanism.

Figure 15 is a detailed perspective view of the key locking mechanism with the parts in the positions they assume to lock the keys.

Figure 16 is a rear elevation showing the machine equipped with a plurality of column registers, a plurality of crossfooters and separate and distinct mechanism controlling the operation of the respective crossfooters.

Figure 17 is a bottom plan view of two crossfooters, or the twin crossfooter, showing the independent controlling devices therefor and a restoring mechanism common to both crossfooters or crossfooter sections; and

Figure 18 is a section showing more particularly the common restoring mechanism for the crossfooter sections.

The illustrated form of the invention has been designed with special reference to the equipment of the Elliott-Fisher bookkeeping machine of commerce. A disclosure of the entire machine is unnecessary, but it may be stated that this type of machine includes a flat platen which supports the work sheet and a printing mechanism which moves longitudinally of the platen for line spacing and transversely of the platen for

letter spacing. To secure this movement of the printing mechanism, it is mounted on a carriage which travels on a line space frame for letter spacing and with said frame for line spacing.

Associated with the machine is computing mechanism consisting of one or more adding devices or registers and one or more master wheels or actuators therefor. Relative 10 denominational movement of a master wheel and the register operated thereby is effected by the movement of the carriage as the latter advances to successive denominational positions and the operative or actuating 15 movement of the master wheel or master wheels is effected as number keys are operated to cause the printing of a number on the work sheet. Thus, when a number is 20 printed on the work sheet in a given column position, a given register will be operated in those denominational positions which correspond with the denominational positions of the printed digits included in the number.

It is also usual in these machines to mount 25 at one end of the carriage an additional computing device known as a crossfooter, automatically controlled for addition or subtraction and operated by its own master wheel in synchronism with one or more of what are 30 known as column registers.

It is thought that this general description will suffice for the present purpose.

The carriage of the machine is indicated by 1, the adding keys 2 and the key levers 3. The levers 3, when swung down by the operation of the keys, effect the rotation of the primary master wheel 4 through the medium of operating connections known as differential mechanism, the specific character of which is not material. It is sufficient to say that this differential mechanism usually includes actuator levers 5, upon which are or may be mounted non-print keys 6, by means of which the adding mechanism may be operated independently of the writing mechanism. Associated with the levers 5 are a series of key locking members 7 which alternate with the levers 5 and are 40 swung from their upper ends. The locking members 7, unless free to swing or spread from an operated lever 5, obstruct all of said levers and lock the keys against actuation. If, however, the members 7 are free to swing, they will permit the depression of any lever, but will lock the remaining levers of the series. This form of key locking mechanism is well-known. Mounted on a register supporting bar 8 in rear of the carriage 1 are column registers 9, any number of which may be employed within the capacity of the bar. The column registers 9 are operated by the master wheel 4 which, as heretofore stated, is advanced by the carriage to the successive number wheels of the registers. At one end of the carriage 1 are

mounted two additional registers 10 and 11, the master wheels 12 and 13 of which are movable longitudinally upon master wheel shafts 14 and 15 driven from the primary master wheel shaft 16. The shaft 16 carries the primary master wheel 4 and is geared through two sets of variable gearing 17 and 18 to the two master wheel shafts 14 and 15. The variable gearing 17 and 18 (more fully described in my copending application No. 469,530, filed May 14, 1921) is automatically controlled to determine whether the registers 10 and 11 shall add or subtract, by control levers 19 and 20 75 coacting with control devices 21 and 22 carried by control bars 23 and 24. It will be noted that the control levers 19 and 20 are located in different vertical and horizontal planes and coact with control devices which are also located in different planes to insure the independence of the control of the two registers 10 and 11. The master wheels 12 and 13 are movable with master wheel carriages 25 and 26 slidable on a guide bar 27 and operated by master wheel advancing mechanisms of well-known form (see my pending application supra). As indicated in Figure 1, each of these mechanisms include a vertical shaft 28, having an upper arm 29 engaging the master wheel 90 carriage and a lower arm 30 engaging stops 31 on the respective control bars 23 and 24. While these master wheel advancing devices are not new, the location of the arms 30 of the respective advancing mechanisms in different planes so that the control of the two registers 10 and 11 is entirely independent, is a feature of this invention. It will now be seen that while the direction of rotation of the shaft 16 and the primary master wheel 4 is constant to operate any column register for addition, the variable gearing sets 17 and 18 may be operated to secure a 95 very wide range of operative possibility between the column register operated and the two additional registers or crossfooters 10 and 11. For instance, when a given column register is operated, neither of the registers 10 and 11 will come into action unless by pre-arrangement of the controlling mechanism. On the other hand, the controlling mechanism may have predetermined that the registers 10 and 11 shall one or both add 100 while the column register is adding, or that one or both shall subtract while the column register is adding, or that one shall add and the other subtract regardless of which register performs the operation. In other words, by means of the specified organization, the two crossfooters or the twin crossfooter, as it may be called, may be caused to operate one at a time for either addition or subtraction, or simultaneously for 105 addition or subtraction, or one for addition and the other for subtraction, irrespec- 110 115 120 125 130

tive of whether or not the column register is operated simultaneously with any of the specified permutations. 32 indicates the usual restoring key or bar which, as is well understood, is depressed to restore the carrying mechanism of the crossfooting register. This bar and the associated mechanism is no different from that ordinarily employed, except that the parts are extended to embrace both registers, or both sections of the twin register.

It has been pointed out that one of the objects of the invention is to provide mechanism which will automatically lock the operating keys when either of the registers 10 and 11 are not in condition for operation, and I shall now proceed to describe the mechanism whereby this end is attained. Associated with the master wheel carriages 25 and 26 are carriage bars 33 and 34 mounted to slide through suitable openings in the walls of the crossfooter casing. These bars are semicircular in cross section and each is fixed to one of the carriages to move therewith. The rear bar 33 of the carriage 25 is provided adjacent to one end with a notch 35 adapted when the master wheel 12 passes out of engagement with the number wheel of lowest order to be engaged by a locking plate 36 mounted on the left-hand end of the crossfooter casing as shown in Figure 3. The locking plate 36 is slotted at 37 and mounted on guide screws 38, being constantly urged toward its elevated locking position by a spring 39. When the master wheel moves out of the register the locking plate 36, by engaging the notch 35 prevents the retraction of the master wheel 12 until the locking plate 36 has been drawn down. This releasing or unlocking movement of the slide is accomplished by the depression of the restoring member 32, one of the side arms of which carries a pin 40 which moves within a longitudinal slot 41 at the lower end of the plate 36. Thus, when the master wheel 12 is moved out of register, it will be locked against retraction to its normal position by the plate 36 which will not be withdrawn from the carriage bar 33 until the restoring mechanism of the register has been operated to restore the carrying mechanism, at which time the master wheel carriage will be unlocked and retracted in a manner well understood in the art. It is desirable, however, that this retraction of the master wheel shall be prevented until the restoring mechanism, the primary element of which is the member 32, has returned to its normal position, and it is also desirable to provide for the automatic locking of the keys when the master wheel moves out of the register and for the retention of the keys in such locked condition as long as any of the parts are out of normal position. That is to say, it is

desirable to keep the keys locked until the master wheel has been fully retracted and the restoring mechanism fully returned to normal position. To accomplish these results, I mount at the right-hand end of the series of locking members 7 a key locking lever 42 fulcrumed at 43 and having its front end 44 normally disposed in non-interfering relation (see Fig. 7) with the adjacent end member 7. This end 44 of the lever, however, is movable into interfering relation with the locking member 7 so that said member cannot yield side-ways and therefore blocks the whole system of locking members and prevents the operation of any key (see Fig. 15). The lever 42 is normally retained in its unlocked position by a spring 45, but is provided with a pendent cam tooth 46 which, when engaged by an oppositely disposed cam tooth 47 on the carriage bar 33 is raised to swing the lever 42 to its locked position. This movement of the key locking lever 42 to lock the keys is effected when the master wheel 12 moved beyond the number wheel of lowest order and as long as the said master wheel remains in the position to which it has just been moved, the tooth 47 will underlie the tooth 46 and the keys will remain locked. Obviously, however, unless provision is made to the contrary, the unlocking of the carriage bar and its consequent retraction upon the depression of the restoring device 32 would move the tooth 47 away from the tooth 46 and thus permit the keys to be unlocked at the beginning of the retractile movement of the master wheel and before the restoring device had returned to normal position. I therefore provide the lever 42 with a down-turned end 48 engaged by the upper end of a full stroke lever 49 fulcrumed at 50 and having a cam slot 51 with which the pin 40 engages. The form of the slot 51 is such that the initial downward movement of the restoring member 32 will cause the pin 40 to swing the full stroke lever 49 to a position in which its upper end will engage the end 48 of the key locking lever 42. As this occurs before the release of the carriage bar 33, it will be evident that the release and retraction of said bar which has accomplished the locking of the keys, will not effect the unlocking thereof because, when the tooth 47 moves out from under the tooth 46 the lever 42 will still be held in locked position by the full stroke lever 49. After the full stroke lever has been moved by the initial downward movement of the restoring member 32, continued movement of said restoring member will not affect the lever 49, but will finally accomplish the described release of the bar 33, the keys remaining locked for the reason stated, until upon the final retractile movement of the restoring lever 32 the full stroke

lever 49 will be returned to normal position, thus permitting the key locking lever 42 to unlock the keys. It is sometimes desirable to lock the register 10 out of action. 5 This is accomplished by moving the master wheel 12 an additional step beyond the number wheels and locking it in such position. To permit this movement, the notch 35 in the bar 33 is sufficiently wide to accommodate an additional step of the master wheel to the right after the notch has been engaged by the locking plate 36. To retain the master wheel in this extreme position, the bar 33 is provided with a second notch 15 52 engaged by a pivoted master wheel lock 53 drawn in one direction by a spring 54 and movable out of engagement with the notch by a crossfooter release key 55. Attention is directed to the fact that when the master wheel is moved to this extreme right-hand position, the keys will be unlocked as the tooth 47 will move beyond the tooth 46 of the locking lever. Therefore, as long as the register remains out of action, the 20 25 keys will be unlocked and capable of independent use. As soon, however, as the release key 55 is operated, the master wheel will merely retract one step as permitted by the notch 35, again bringing the cam 30 teeth 46 and 47 into coincidence to lock the keys, in which condition they must remain, as we have seen, until all parts are in operative condition. All of the various characteristics of the bar 33, as described, are 35 possessed by the bar 34 which moves with the master wheel carriage 26 of the other register 13. This bar is likewise provided with a notch 35^a corresponding with the notch 35 and similarly engaged by a locking plate 36^a corresponding with the locking plate 36, but preferably located at the opposite side of the casing. Also, the bar 34 is provided with the locking notch 52^a corresponding with the notch 52, but instead of being directly engaged by extension of the release key, this notch is engaged by a locking member 53^a drawn toward its engaging position by a spring 54^a and having a projection 54^b engaged by a cam 54^c on 40 45 50 55 the lever of the release key 55^a. This slight variation of construction is necessitated by the requirement for having similar mounting for the release keys 55 and 55^a notwithstanding engagement with two opposite disposed bars.

From what has been said, it will be observed that the two computing devices on the carriage are operated separately or simultaneously by the same operating keys and that with said keys is associated key locking mechanism controlled by either computing device to automatically lock the keys after the computing device has been operated to register a number and arranged to retain the keys in locked condition until the

computing device has either been put out of action or fully retracted to normal condition if retained in action.

The invention as herein claimed, however, does not comprehend the broad idea of a single computing device controlling the operation of the keys under the conditions stated, but is directed specifically to the controlling mechanism and to the somewhat broader idea of key locking means controlled by any one of a plurality of computing devices.

While I have illustrated in detail the restoring mechanism for the twin crossfooter, I have not deemed it necessary to describe this structure in the same detail. This is for the reason that it is substantially like the restoring mechanism, fully described and claimed in my copending application No. 434,254, filed December 31, 1920, except that, as already stated, the restoring mechanism herein illustrated is of sufficient width to embrace both crossfooter registers, or sections of the twin crossfooter.

This variation is accomplished by mounting the various side members of the restoring mechanism at opposite sides of the twin crossfooter casing and by making the transverse members of the restoring mechanism of sufficient length to serve the carrying devices of both crossfooters.

It is thought that from the foregoing, the arrangement and operation of the illustrated construction will be clearly understood, but I reserve the right to effect such structural modifications and variations as may come fairly within the scope of the protection prayed.

What I claim is:

1. In a machine of the character described, the combination with a frame and carriage, of a plurality of computing devices mounted on the frame, a plurality of computing devices mounted on the carriage, and operating means common to all the said computing devices and mounted on the carriage.

2. In a machine of the character described, the combination with a frame and carriage, of a plurality of computing devices mounted on the frame, a plurality of computing devices mounted on the carriage, operating mechanism mounted on the carriage and common to all the computing devices and arranged to effect their simultaneous operation, and means for determining whether certain of said computing devices shall operate for addition or subtraction.

3. In a machine of the character described, the combination with a frame and carriage, of a computing device mounted on the frame, a plurality of computing devices mounted on the carriage, operating mechanism also mounted on the carriage and common to all the said computing devices and arranged to effect simultaneous operation

thereof, and automatic means for determining whether one, all or none of the computing devices mounted on the carriage shall operate.

6. 4. In a machine of the character described, the combination with a frame and carriage, of a computing device mounted on the frame, a plurality of computing devices mounted on the carriage, operating mechanism mounted on the carriage and common to the several computing devices and arranged to operate the same simultaneously, and automatic means for determining the character of operation of each computing device mounted on the carriage.

5. In a machine of the character described, the combination with a frame and carriage, of a computing device mounted on the frame, a plurality of computing devices mounted on the carriage, operating means mounted on the carriage and common to all the computing devices, and separate controlling mechanism for each of the computing devices mounted on the carriage to determine whether said computing devices shall operate and the character of such operation.

6. In a machine of the character described, the combination with a frame and carriage, of a plurality of computing devices mounted on the carriage and operated for addition or subtraction, and controlling mechanism for said computing devices said controlling mechanism including control bars located in different vertical planes on the frame and control members adjustable along said bars.

7. In a machine of the character described, the combination with a frame and carriage, of a series of computing devices mounted on the frame, a plurality of computing devices mounted on the carriage, and operating mechanism mounted on the carriage arranged to operate each of the registers on the frame and to operate, simultaneously with each of said computing devices, one or more of the computing devices on the carriage.

8. In a machine of the character described, the combination with a frame and carriage, of a series of computing devices mounted on the frame, a plurality of computing devices mounted on the carriage, and controlling mechanism operated by the movement of the carriage to control both the operation and the character of the operation of the computing devices mounted on the carriage and including devices independently settable on the frame and longitudinally of the carriage travel.

9. In a machine of the character described, the combination with a frame and carriage, of a plurality of computing devices mounted on the frame, a primary actuator mounted on the carriage and presentable to

successive computing devices mounted on the frame, secondary actuators for the computing devices mounted on the carriage, and operating means common to the several actuators.

10. In a machine of the character described, the combination with a frame and carriage, of a plurality of computing devices mounted on the frame, a primary actuator mounted on the carriage and presentable to successive computing devices mounted on the frame, secondary actuators for the computing devices mounted on the carriage, and separate controlling mechanism for each of the secondary actuators.

11. In a machine of the character described, the combination with a frame and carriage, of a plurality of computing devices mounted on the frame, a primary actuator mounted on the carriage and presentable to successive computing devices mounted on the frame, secondary actuators for the computing devices mounted on the carriage, and separate controlling mechanism for each of the secondary actuators said controlling mechanism being operated to determine whether the secondary actuator shall operate its computing devices.

12. In a machine of the character described, the combination with a frame and carriage, of a plurality of computing devices mounted on the frame, a primary actuator mounted on the carriage and presentable to successive computing devices mounted on the frame, secondary actuators for the computing devices mounted on the carriage, and separate controlling mechanism for each of the secondary actuators said controlling mechanism being operated to determine whether the secondary actuator shall operate its computing devices and whether said computing devices shall be operated for addition or subtraction.

13. In a machine of the character described, the combination with a frame and carriage, of a plurality of computing devices mounted on the frame, a plurality of computing devices mounted on the carriage, a master actuator mounted on the carriage and arranged to operate each of the computing devices mounted on the frame, a plurality of secondary actuators mounted on the carriage to operate the computing devices thereon, variable gearing between the secondary actuators and the primary actuator, and automatic means controlling said variable gearing.

14. In a machine of the character described, the combination with a frame and carriage, of a plurality of computing devices mounted on the frame, a plurality of computing devices mounted on the carriage, a master actuator mounted on the carriage and arranged to operate each of the computing devices mounted on the frame, a plu-

rality of secondary actuators mounted on the carriage to operate the computing devices thereon, a set of variable gearing for each secondary actuator, and controlling mechanism associated with each secondary actuator and its variable gearing and variable to determine whether a given secondary actuator shall operate its computing device and whether such actuation shall be for addition or subtraction.

15. In a machine of the character described, the combination with a plurality of computing devices and operating keys therefor, of key locking mechanism, and means associated with each of the computing devices to lock the keys after each computing device has been operated completely and to unlock the keys when the parts of each computing device have been restored to normal position.

16. In a machine of the character described, the combination with a plurality of computing mechanisms and operating keys therefor, of key locking mechanism controlled by each of the computing mechanisms, and operative to lock the keys after each complete operation of a computing mechanism.

17. In a machine of the character described, the combination with a plurality of computing mechanisms including denomination selecting devices, of a series of adding keys, key locking mechanism, and means for causing each denomination selecting device to operate the key locking mechanism.

18. In a machine of the character described, the combination with a series of keys, and a plurality of computing mechanisms each including a series of number wheels and a master wheel, of key locking mechanism, and means whereby the movement of either master wheel beyond the adjacent number wheels will cause the key locking mechanism to lock the keys.

45. 19. In a machine of the character de-

scribed, the combination with a series of keys, and a plurality of computing mechanisms each including a series of number wheels and a laterally movable master wheel, of key locking mechanism, and means for causing the locking mechanism to lock the keys when either master wheel is in a pre-determined position and to unlock the keys when such master wheel moves from such pre-determined position in either direction.

20. In a machine of the character described, the combination with a series of keys, of computing mechanism including a plurality of denomination selecting devices, carrying mechanisms and restoring mechanism for the carrying mechanism, of key locking mechanism controlled conjointly by the denomination selecting devices and the restoring mechanism.

21. In a machine of the character described, the combination with a series of keys, a computing mechanism including carrying mechanism, a plurality of denomination selecting devices and a single restoring mechanism for the carrying mechanism, of key locking mechanism effective to lock the keys when any selecting device moves to a given position, and means operative by the restoring mechanism to unlock the keys.

22. In a machine of the character described, the combination with a series of operating keys, a computing mechanism including a plurality of denomination selecting devices, key locking mechanism including a locking lever, and means movable with each denomination selecting device to move the locking lever.

In testimony whereof I hereunto affix my signature in the presence of two witnesses.

HARRY ARTHUR FOOTHORAP.
